UNITED STATES PATENT OFFICE.

GEORGE F. MAJOR, OF BRANDY STATION, VIRGINIA.

STEAM-BOILER.

SPECIFICATION forming part of Letters Patent No. 252,113, dated January 10, 1882.
Application filed July 7, 1881. (No model.)

To all whom it may concern:

Be it known that I, GEORGE F. MAJOR, of Brandy Station, in the county of Culpeper and State of Virginia, have invented a new and useful Improvement in Steam-Boilers, of which the following is a full, clear, and exact description, reference being had to the annexed drawings, forming part of this specification.

My invention relates to tubular boilers in which the tubes are arranged side by side; and it consists in the peculiar construction of a tube having a reduced end and the alternately-reversed arrangement of two or more series of such tubes; each series of which is connected with a drum at each end, with the drums so disposed as to form flues between the series of tubes, as hereinafter described.

In the accompanying drawings, Figure 1 is a plan view of my improvement; Fig. 2, a side elevation. Fig. 3 is an end elevation; Fig. 4, one of the tubes, and Figs. 5 and 6 represent details of the tube.

A represents a fire-box, in each side of which are arranged two parallel series of tubes, B. The said tubes are slightly inclined from a vertical position with the steam-drums C, to one of which the upper ends of each series are connected, lying in juxtaposition in a horizontal plane, while the lower ends of each series are connected with a mud drum, D. The two inner opposite series are composed of tubes which have their reduced portions b connected with the steam-drums C to form draft-passages to the flues c between the inner and outer series, and the reduced portions of the tubes in the outer series are connected with the mud-drums D to form similar passages from the flues c to the flues d leading to the smoke-pipe. The steam-drums C are connected at one end by a drum, C', and the mud-drums D are likewise connected by a drum, D'.

As the joints of the tube B are exposed to the action of great heat, I prefer to construct them in the following manner: The large portion of the tube, which connects with one of the drums, is screwed onto the larger end of the tapering double-threaded plug b², and the smaller end of the said plug is screwed into a threaded perforation in the drum. The oppo-

site end of the tube B is jointed to a reduced section, b, of about one-half the size of the tube in diameter, by means of an exterior tapering threaded collar, b³, which screws into said end.

The projecting end of the reduced section b is provided with an exterior screw-thread, onto which the threaded thimble c' is screwed. This thimble is made tapering on its outer surface, which is screw-threaded and provided with a longitudinal slit, c², extending from end to end, into which a copper strip, d', is inserted in order to produce a binding effect by the yielding of the copper when the tapering end is screwed into the apertured drum. With this construction the joints of the said parts are enabled to resist the action of the intense heat to which they are exposed. I am aware that a boiler-tube having a reduced section at one end is not broadly new; but I am not aware that such a tube has before been adapted for the peculiar combination above described.

It will be seen that the drums, which are made twice as large in diameter as the tubes, by being placed in juxtaposition, will serve to hold the series of tubes sufficiently apart to form the flues necessary for the passage of the products of combustion along the surface of the tubes to the smoke-pipe.

It is obvious that the tubes may be arranged in various other positions than that shown in the drawings without departing from the spirit of my invention, the main principle being that the tubes shall be arranged in alternately-reversed series, whereby the reduced portions of the tubes shall assist in forming continuous flues for conveying the heated gases along the two sides of each series from end to end.

Having thus described my invention, what I claim is—

1. In combination with the tube B and drum C, the tapering thimble c', having the longitudinal slit c² and the copper strip d', substantially as shown and described, and for the purpose set forth.
2. In combination with the drums C and D, the series of inclined tubes B, having reduced portions, as described, and so arranged as to form draft-passages at the upper and lower ends of said series alternately, which shall com-

communicate with flues between the series, as and for the purpose specified.

3. The combination of the tubes B, having double-threaded plug b¹, reduced section b², having threaded collar b³, and the thimble c¹, having slit c² and copper strip d¹, substantially as shown and described, the said tubes being

arranged in alternately-reversed series and combined with drums so as to form flues between the said series, as set forth.

GEORGE F. MAJOR.
